Theodore Ornas, Jr., Fort Wayne, Ind., assignor to International Harvester Company, a corporation of New Jersey

Application May 5, 1954, Serial No. 30,336

Term of patent 7 years

(Cl. D14—3)

To all whom it may concern:

Be it known, that I, Theodore Ornas, Jr., a citizen of the United States, residing at Fort Wayne, in the county of Allen and State of Indiana, have invented a new, original, and ornamental Design for a Vehicle Cab, of which the following is a specification, reference being had to the accompanying drawings, forming part thereof, in which:

The dot-dash line shown in the drawing figures is for illustrative purposes only.

I claim:

The ornamental design for a vehicle cab, substantially as shown and described.
